UNITED STATES PATENT OFFICE.

ANDERS JORDAHL, OF BERLIN, GERMANY.

CENTERING FOR REINFORCED-CONCRETE FLOORS AND ROOFS.

1,241,124.

Specification of Letters Patent. Patented Sept. 25, 1917.

Application filed November 14, 1914. Serial No. 872,161.

To all whom it may concern:

Be it known that I, ANDERS JORDAHL, a citizen of the Kingdom of Norway, and residing at Berlin, Germany, have invented 5 certain new and useful Improvements in Centering for Reinforced-Concrete Floors and Roofs, of which the following is a specification.

My invention relates to centering or false-work for making reinforced concrete floors and roofs, of the type consisting of beams and slabs, sheet-iron molds of U-section being employed for forming the hollow spaces between the beams.

15 According to my invention the sheet iron molds are divided longitudinally into two parts, the horizontal legs of which rest on and are lightly attached to easily removable supports under the slab, while the edges of 20 the vertical legs rest on sheeting boards or the like under the beams provided with longitudinal grooves or other means for holding the molds in position. The legs of the 25 molds are preferably of unequal length in order to enable one and the same section to be employed for beams of different height and different distances apart.

To these and other ends my invention consists in the construction, arrangement 30 and combination of parts described herein-after and pointed out in the claims.

One illustrative embodiment of my invention and modifications thereof are represented by way of example in the accompanying 35 drawing, wherein:—

Figure 1 is a cross-section through one form of centering according to my invention,

Fig. 2 is a cross-section showing a modification, and

Fig. 3 is a cross-section showing another modified form, in which the distance between the beams of the floor or roof is greater than in the form shown in Fig. 1.

45 Firstly referring to Fig. 1 the centering comprises scaffolding *a* which carries sheeting boards or form sections *b* running in the longitudinal direction of the beams. These boards *b* are provided with longitudinal 50 grooves or other means for holding the molds into which are inserted the lower edges of L-shaped sheet iron molds or form sections *e*, but in the forms shown the grooves or means are located inwardly of the vertical legs of the molds and said grooves open upwardly and have their outer walls

sloping outwardly and upwardly, while the inner walls preferably extend substantially vertically. The horizontal legs of these molds rest on and are temporarily secured 60 to the supporting boards or form sections *c* running in the longitudinal direction of the beams. These boards *c* are carried by upright supports *d* which rest on and are detachably connected to the scaffolding *a*. 65

Each pair of L-shaped mold-sections bearing with their horizontal legs on the same board *c* form an inverted U-section—on which the concrete can be conveniently poured or rammed. The sheet iron molds 70 can be easily removed immediately after the hardening of the thin concrete slab *g* without disturbing the supports *b* of the beams *f*. When it is desired to do this, the supports *d* and the boards *c* are removed 75 and the mold sections *e* are tilted downward about their lower edges supported in the grooves in the sheeting boards *b*, as is indicated in dotted lines in Fig. 1.

As shown in Fig. 1, the legs of the L-shaped mold sections are of uneven length, 80 in order to enable various heights of beams and various distances between the beams to be formed without changing the mold-sections.

As will be understood from Fig. 2 another change in height can be made by placing on the sheeting boards or form sections *b* distance blocks *h* which are preferably provided above with sheet-iron clips *i* having a 90 groove corresponding to the groove in the boards or form sections *b*. The grooves prevent injury of the possibly not quite hardened concrete by the edges of the molds *e* which are engaged in the grooves in the 95 sheeting boards when the same are tilted. This action is due to the fact that the mold sections may swing downwardly and inwardly as shown in dotted lines in Fig. 1, after the center or upright intermediate 100 supports are removed, the sloping walls of the grooves permitting this, while the inner or vertical walls of the grooves in substantially vertical alinement with the opposite walls of the beams *f* bear the weight of the 105 molds until they are removed and limit the displacement of the molds in the opposite directions facing said vertical walls whereby uniformity in the thickness of the beams is insured.

110 The molds are preferably made in lengths of one to two meters, but they may, of

course, be made shorter or longer. In order to prevent the concrete adhering to the molds it is preferable to coat them with oil-paint or soap before use. If desired, the 5 molds *e* may be made of any other suitable material.

After the entire centering has been removed the spaces between the ribs may be closed by attaching metal lath or the like 10 under the ribs and afterward plastering same.

The modification shown in Fig. 3 differs from that just described only in that flat sheets *l* are arranged on intermediate false-work 15 between the L-shaped molds *e*, so that the reinforced concrete beams may be at a greater distance apart as is required in ordinary floors or roofs of the type shown.

It is to be understood that the supporting 20 boards *c* may be made broader or narrower according to as a greater or smaller distance between the beams is required. Also, the continuous sheeting boards *b* may be made broader if it is wished to make a beam of 25 greater thickness.

Having now described my invention what I claim is:

1. In centering for reinforced concrete floors and roofs of the type consisting of 30 beams and slabs the combination with longitudinal members immediately supporting the beams and being provided with longitudinal grooves and a removable upper longitudinal support under the slab, of a pair of L-shaped molds the horizontal legs of which rest on and are attached by means 35 of nails to the said removable support under the slab and the vertical legs of which rest in grooves in the said longitudinal members under the beams, said grooves having inner walls substantially in alinement with the walls of the beams and outer walls permitting downward movement of the molds out of contact with respect to the beams.

45 2. In centering for reinforced concrete floors and roofs of the type consisting of beams and slabs the combination with longitudinal members immediately supporting the beams and being provided with longitudinal 50 grooves and a removable upper longitudinal support under the slab, of a pair of L-shaped molds each having legs of unequal length, the horizontal legs of which rest on and are attached to the said removable support under the slab and the vertical legs of which rest in grooves in the said longitudinal members under the beams, said grooves being located inwardly of or under the vertical faces of the beams whereby the 55 molds may swing downwardly out of contact with any portion of the beams for removal without injuring the same.

3. In centering for reinforced concrete floors and roofs of the type consisting of 60 beams and slabs, the combination with scaf-

folding of longitudinal members carried by same immediately supporting the beams and being provided with grooves, a removable intermediate support under the slab carried by the scaffolding and a pair of L-shaped molds carried in the grooves or the like of longitudinal members under the beams and by the intermediate support under the slab, said grooves having vertical walls toward the beams and outer walls extending therefrom, whereby the molds may be caused to bear against said vertical walls below the beams when displaced from the beams and slabs.

4. In centering for reinforced concrete 80 floors and roofs of the type consisting of beams and slabs, the combination with scaffolding; of longitudinal members carried by same immediately supporting the beams and being provided with grooves, a removable intermediate support under the slab carried by the scaffolding, a flat sheet of metal plate carried by the intermediate support and a pair of L-shaped sheet metal molds carried by said plate and resting in 85 the grooves of the longitudinal members supporting the beams, said grooves having vertical walls to limit the displacement of the molds toward each other at their portions engaging the grooves but to permit 90 free swinging of the molds in the opposite directions as and for the purposes specified.

5. In a centering for reinforced concrete 95 floors and roofs having beams and slabs, supporting members, spaced and horizontally extending form-sections, a pair of L-shaped form-sections for each of said horizontal sections, each L-shaped form-section having one leg supported on an opposite longitudinal edge of the horizontal form-section in a vertical position and having the other leg extending laterally in an opposite direction, a removable intermediate 100 form-section supported by said supporting members and having the free ends of the 105 opposing horizontal legs of the L-shaped form-sections to rest thereupon, and means for normally preventing lateral movement of the vertical legs of the said L-shaped form-sections, but adapted to permit said 110 L-shaped sections to be tipped inwardly away from the beams when the intermediate form-section is removed, whereby the beams will not be injured by the edges of the first-named leg portions which rest on the horizontal form-sections.

6. In centering for a reinforced concrete 115 structure of the character described, having beams, longitudinal members supporting the beams, and molds for the beams resting on 120 said members, said members having longitudinal grooves with sloping walls extending away from the face of the beams and vertical walls located inwardly of the faces of the beams to permit displacement of the 13

molds from the slabs and beams downwardly out of contact with the faces of the beams.

7. In centering for reinforced concrete floors and roofs of the type consisting of beams and slabs, the combination with longitudinal members immediately supporting the beams and a removable upper longitudinal support under the slabs; of a pair 10 of L-shaped sheet iron molds each having legs of unequal lengths, the horizontal legs of which rest on and are temporarily fas-

tened to said removable supports under the slabs and the vertical legs of which rest in grooves to prevent lateral displacement on 15 the said longitudinal members under the beams.

In testimony whereof I have signed my name in the presence of two witnesses.

ANDERS JORDAHL.
